UNITED STATES PATENT OFFICE.

WILLIAM MARTIN, OF SALEM, MASSACHUSETTS, ASSIGNOR OF ONE-HALF
TO THOMAS F. LITTLE, OF SAME PLACE.

MECHANICAL MOVEMENT.

SPECIFICATION forming part of Letters Patent No. 591,102, dated October 5, 1897.

Application filed February 19, 1897. Serial No. 624,130. (No model.)

To all whom it may concern:

Be it known that I, WILLIAM MARTIN, a citizen of the United States, residing at Salem, in the county of Essex and State of Massachusetts, have invented certain new and useful Improvements in Mechanical Movements, of which the following is a specification, reference being had therein to the accompanying drawing.

10 My invention consists in a new and useful combination and arrangement of levers and links whereby conveniently to apply and transmit power to the desired part of a machine in order to communicate movement to the said part and lift a load of any given character or perform other useful work tending to consume power, all as presently will be described with reference to the accompanying drawing.

20 The distinguishing characteristics of the invention will be more particularly pointed out and distinctly defined in the claims at the close of this specification.

The accompanying drawing illustrates diagrammatically the mechanical movement embodying my invention and in dotted lines illustrates the positions assumed by the parts after being moved from their full-line position.

30 At 1 is a lever which is intended, for instance, to be actuated by power applied thereto by hand, the upper end thereof being represented as suitably shaped to be grasped by the hand of the operative.

35 At 2 is the pivotal point around which the said lever turns. I have represented the said lever as having arranged close thereto an arc or segment with notches 4 therein, the lever having pivoted thereto a latch 5, to which latter is connected a rod 6, having the upper end thereof pivoted to a releasing-lever 7, which last in turn is pivoted at 8 to the upper part of the lever 1.

40 At 9 is a spiral spring surrounding the rod 6 and compressed between the latch 5 and the guide-piece 10, the said piece 10 being secured to the lever 1, and through it the rod 6 passes. The spring 9 acts normally to hold the said latch 5 in one of the notches 4 of the arc or segment 3. Whenever desired, as when it is necessary to shift the lever 1 from one posi-

tion to another, the latch may be raised out of the notch 4, in which it happens to be for the time being, through the medium of power applied by hand, to the releasing-lever 7, and when the pressure upon the said lever 7 is released the spring 9 will act to force the said latch into the next notch which is presented thereto in the movement of the lever. The lower arm of the lever 1 is curved or projected 55 rearwardly or to the left of the pivotal point, as clearly shown in the drawing, and to the extremity of the said lower arm of the lever 1 is joined one extremity of the curved link 11, the right-hand extremity of which is joined 60 to the lower arm of a lever 12, which is shown pivoted at 13 upon a small stand 14, which is supported in any suitable manner.

The upper arm of the lever 12 is curved for the purpose which presently will be explained, 70 the concave side thereof being presented toward the left in the drawing, and the upper extremity of this arm of the said lever 12 is joined by a curved link 15 to the upper extremity of an arm 16, that is mounted upon 75 a rock-shaft, which is shown at 17. To the rock-shaft 17 is applied the part which sustains the load or performs the work. In the drawing I have represented an arm 18 fast upon the said rock-shaft 17, and for convenience in illustrating the idea I have shown conventionally a load 19, carried by the said arm 18. The resistance or load which is transmitted to the rock-shaft 17 by the work to be done or the burden to be supported acts or 80 reacts in a direction to raise the lower arm of the lever 12 and also carry upwardly the link 11. The said link 11 is contemplated in practice to serve as a means of counterbalancing the load 19 or the resistance applied to the 85 said shaft 17. In practice I apply to the said link 11 counterbalancing-weights 20, one or more of which may be used, according to requirements. The rearward projection of the lower arm of the actuating-lever 1 causes a 90 part of the weight 11 to be applied to the said lever 1 to the left-hand side of the fulcrum or pivot 2 of the said operating-lever 1, and thereby facilitates the starting of the parts and load into movement, it being borne in 95 mind that the said load or resistance to be overcome is partly or wholly counterbalanced

by said link 11. The rearward projection of the lower arm of the lever 12 disposes the said arm in an approximately horizontal position when the load 19 is at its lowest point, and 5 thereby enables the weighted link 11 to act to the greatest possible advantage in facilitating the starting of the load into movement. The pivot 13 of the lever 12 is almost immediately below the rock-shaft 17, and on this 10 account, in order to permit the full movement of the upper arm of the lever 12 to the left in the drawing, the said arm is curved, as aforesaid. This enables the upper end of the said curved arm to pass over and beyond the rock- 15 shaft 17 to the position which is shown by dotted lines in the drawing. The extended sweep of the lever 12, which thereby is permitted, causes the pivot connecting the upper arm of the lever 12 with the extremity of the 20 lever 15 to approach in the movement of the lever toward the dotted-line position more and more closely the line connecting the axis of the rock-shaft 17 and the axis of the pivot which joins the link 15 to the arm 16, there- 25 by producing a toggle-like effect. The curved form of the links 11 and 15 gives ease and freedom, with an absence from binding, to the movement of the parts, which conduces to the attainment of the desired results.

30 The improved mechanical movement herein shown and described is applicable to use

in various connections and machines. One use for which it is fitted is in connection with railway-crossing gates, but I do not limit myself to such use.

35

What I claim is—

1. The combination with the actuating-lever 1, of the link 11, the lever 12, the link 15, the arm 16, and the rock-shaft 17, all substantially as and for the purposes set forth. 40

2. The improved mechanical movement comprising in combination, the actuating hand-lever 1, having the recurved lower arm, the weighted curved link 11 having one extremity thereof connected pivotally with the 45 said curved lower arm, the lever 12 having the other extremity of the link 11 connected pivotally therewith and having also the curved upwardly-extending arm, the curved link 15 having one extremity thereof connected pivotally with the said upper arm of the lever 12, the arm 16 having the other extremity of the said link 15 connected pivotally therewith, and the rock-shaft 17 having the said arm 16 made fast thereon, substantially as described. 50

In testimony whereof I affix my signature in presence of two witnesses.

WILLIAM MARTIN.
